CLAIM

The ornamental design for a bag handle cover, as shown and described.

DESCRIPTION

FIG. 1 is a front view of a bag handle cover illustrating the new design;

FIG. 2 is a rear elevational view thereof;

FIG. 3 is a top elevational view thereof;

FIG. 4 is a bottom side elevational view thereof;

FIG. 5 is a right side elevational view thereof; and,

FIG. 6 is a left side elevational view thereof.

The broken lines in the drawings are included for the purpose of illustrating portions of the bag handle cover that form no part of the claimed design.
